UNITED STATES PATENT OFFICE.

FRANK E. BEARDSLEY, OF TRAVERSE CITY, MICHIGAN.

DOOR-KNOB FASTENER.

941,906.

Specification of Letters Patent. Patented Nov. 30, 1903.

Application filed November 18, 1903. Serial No. 433,215.

To all whom it may concern:

Be it known that I, FRANK E. BEARDSLEY, a citizen of the United States, residing at Traverse City, in the county of Grand Traverse and State of Michigan, have invented 5 a new and useful Door-Knob Fastener, of which the following is a specification.

This invention relates to door knobs, and particularly to means whereby the knobs 10 may be fastened upon the spindle, the object of the invention being to provide a fastening device whereby the knob may be rigidly fastened to the spindle and adjusted along the spindle at any point desired but 15 preventing the removal of the knob from the spindle.

A further object is to provide a novel fastening device whereby the knob may be attached to the spindle without the necessity 20 of screw holes being made in the spindle, thereby weakening the same, and thus doing away with the expense of drilling and tapping these holes.

My invention also does away with the 25 lead-bushing in the knob and the usual screw and washers.

My improved fastening device allows the 30 knob to be adjusted accurately without the use of tools and by any unskilled workmen.

My invention consists in providing a hollow 35 knob with one or more inwardly projecting tongues or pawls, preferably struck up from a sheet metal blank, which pawls project outward and permit the spindle to be inserted into the knob, but when the knob 40 is drawn upon jam upon the spindle, thus preventing the withdrawal of the knob there being provision for the insertion of a key through the sides of the knob whereby the 45 pawls may be raised when desired to permit the knob to be removed.

In the drawings:—Figure 1 is a side view 50 of a door spindle with its opposed knobs, one of these knobs being shown in section.

Fig. 2 is an interior face view of the inner 55 member or body of the knob. Fig. 3 is a face view of the bridge plate with its tongues. Fig. 4 is a perspective view showing the interior of the body of the knob with the bridge plate in place and a key inserted whereby the tongues are raised to permit the withdrawal of a spindle.

Similar reference numerals designate corresponding parts in all the figures of the 55 drawings.

In the drawings, 2 designates the ordinary

square spindle of a door knob, and 3 one member or body portion of the shell of a knob. This is preferably made of sheet metal, and may be made in any desired 60 form. The center of the sheet metal shell 3 is formed with a square opening 4 through which the spindle 2 passes. The open end of the body 3 is covered by the cap 5 which may be attached to the body in any desired 65 way as by the interlocking flanges 6.

A plate 7 preferably of sheet steel is attached to the interior face of the body 3 in any suitable manner as by soldering along the margins 8. This plate 7 extends across 70 the interior space of the body 3, and has formed in it the opposed tongues 9. The inner ends of the tongues are provided with non-circular recesses for engaging opposite 75 sides of the smooth knob spindle. When the tongues are pressed outwardly, the opening 10 forms angular recesses for receiving the 80 opposite edges of the knob spindle other than those engaged by the spring tongues 9, so that the plate 7 cooperates with the non- circular opening 4 to prevent turning of 85 the knob independently of the spindle. The bridge plate 7 is of course formed with a square aperture 10 through its center for the passage of the spindle 2, and the tongues 9, 90 are notched at their extremities so as to engage with the corners of the square spindle 2. The plate 7 forms a transverse partition 95 in the knob, and the inner end of the knob spindle 2 fits in the opening 10, so that the said opening co-operates with the opening 4 to firmly hold the knob in place against lateral movement transversely to the spindle 2.

It will be seen from Fig. 3 that the tongues 95 are struck up from the blank of the bridge plate 7, and that the blank is so formed that the ends of these tongues project somewhat inward of the square opening 10. This is so that when the tongues are flattened into the 100 same plane as the bridge plate 7 or when there is any force acting to bring these tongues into this plane, they will tend to contract the opening between their ends. Thus when an attempt is made to withdraw 105 the spindle from the knob, the tongues will jam and grip upon the corners of the spindle, biting into the same and preventing any relative movement between the spindle and the knob. As stated above, I prefer to use 110 sheet steel to form the bridge plate 7 and tongues 9 as this material will give requisite

stiffness and strength to the tongues 9 to prevent any chance of their yielding and permit the notched ends of the tongues to bite into and grip upon the spindle 2.

- 5 While the knob as shown, may be easily inserted upon a spindle in the position shown in Fig. 1, it will be impossible to withdraw the knob from engagement with the spindle, and in order to permit this withdrawal I 10 provide the body 3 with the openings 11 so located in the body that the instrument inserted through the openings may be inserted also behind the tongues in their elevated position, and thus hold them outward and 15 permit the withdrawal of the spindle.

In Fig. 4 I show the instrument or key for this purpose inserted through the holes. The key 12 consists of a staple-shaped instrument of wire having two parallel arms 20 13 adapted to be inserted through the openings 11 on either side of the spindle 2 and between the ends of the tongues 9 and the face of the bridge plate 7. It will be seen that this key may be operated to raise the 25 tongues from engagement with the spindle and permit the knob to be withdrawn, and that unless some such instrument thus is used, it will be impossible to withdraw the knob 4. It will also be seen that the knob 30 may be pushed back upon the spindle as accurately and delicately as need be, and that it will be held on any portion of the spindle. The delicacy with which the knob may be 35 adjusted is due to the fact that there are no ratchet teeth with which the pawl-like tongues 11 engage but that the tongues have a constant engagement inward along the whole edge of the spindle.

It will be seen that my improved fastening device is simple and extremely cheap; that it is strong and durable; does away with expensive drilling and tapping; permits the knob to be set into close contact with the door; has no screws to become loose 45 and drop out; that it can be easily removed when desired, and that unless the pawls are lifted, the knob cannot be withdrawn from its engagement with the spindle. It will also be seen that the bridge plate, supported 50 as it is within the shell of the knob, forms a brace or support to the spindle, thus preventing the knob from getting out of alinement with the spindle or becoming loose and shaky. The spindle is supported at two 55 points, namely, where it enters the knob and by the bridge plate, where it is held fast by the tongues.

While I have shown opposed tongues 9 I do not wish to be limited to this, though 60 this is the best form. One tongue might be used, engaging with the corner or side of the spindle. I have shown these tongues as engaging with the corners of the spindle, and I believe that this is the best, but I may also 65 make my device with the tongues engaging

the flat sides of the spindle without departing from the spirit of my invention. The actual details of making these tongues and supporting them within the shell 3 might be varied though I believe the manner shown 70 to be the simplest and most practicable.

From the foregoing it is thought that the construction, operation and many advantages of the herein described invention will be apparent to those skilled in the art without further description, and it will be understood that various details of construction may be resorted to without departing from the spirit or sacrificing any of the advantages of the invention.

Having thus fully described my invention, what I claim as new and desire to secure by Letters Patent, is:—

1. A hollow door knob having a plate attached transversely across its interior formed with a spindle opening in its middle and with an integral spring tongue centrally and outwardly projecting and adapted to engage with said spindle to prevent the withdrawal thereof.

2. A hollow sheet metal door knob having a spindle opening in one side and having a plate of sheet metal attached to the interior of the knob and crossing the same transversely, said plate having a central opening 95 for the passage of the spindle in alinement with the spindle opening in the knob, and opposed resilient tongues struck up from the plate, said tongues, when closed, centrally projecting beyond the edges of the 100 opening in the plate and adapted to be forced outward by a door spindle inserted into the knob in one direction but to grip said door spindle upon a retractile movement thereof.

3. A hollow door knob having in its interior a transverse metal plate provided with a central many-sided opening and opposed resilient tongues struck up from the plate, said tongues projecting centrally and outwardly 110 and having each a spindle engaging notch in its outer end adapted to engage on both sides of a spindle inserted through said knob and the central opening of the plate to prevent the withdrawal of the knob from said 115 spindle.

4. A hollow door knob having in its interior opposed spring tongues adapted to engage with a door knob spindle to prevent the withdrawal of the knob from the spindle, 120 said knob having openings in its side opposite to said tongues to permit the insertion of an instrument to engage with and raise the tongues from engagement with the spindle.

5. A hollow door knob shell having a spindle opening and a transverse plate crossing the interior of the shell in line with the spindle opening, said plate having opposed centrally and outwardly projecting integral 130

tongues adapted to engage with a spindle to prevent its withdrawal, the door knob shell being provided with a pair of perforations in one side, each of the perforations being in 5 alinement with one of the tongues to permit the introduction of an instrument to raise the tongues from engagement with the door spindle.

6. A hollow door knob having an opening 10 for receiving a knob spindle, a partition housed within the knob having an opening alining with the knob opening, and means carried by the partition for gripping the knob spindle to lock the knob thereon.

15 7. A hollow door knob having a spindle-receiving opening, a transverse plate separate from the door knob and secured wholly therein, said plate having an opening disposed in alinement with the opening of the 20 knob to receive the inner end of the knob spindle, and a yielding dog carried by the plate to grip the knob spindle to lock the knob thereon.

8. A device adapted to be secured in a 25 hollow knob for attaching the latter to its spindle, comprising a plate having a non-circular opening, and a spring tongue integrally connected with the plate and arranged with its free end normally extending into 30 the opening.

9. A device adapted to be secured in a 35 hollow knob for attaching the latter to its spindle, comprising a plate having an opening, and oppositely-disposed spring tongues struck out from the opening and arranged

with their free ends normally projecting into the opening and yieldable to either side of the plate.

10. A device adapted to be secured in a 40 hollow knob for attaching the latter to its spindle, comprising a plate of resilient metal having opposed angular recesses forming seats to receive the knob spindle, and yielding tongues struck out from the plate and having angular recesses for gripping the 45 spindle.

11. A door knob comprising a hollow body, a member fixed therein and having a non-circular opening, and spring tongues carried by the member and provided with 50 angular recesses at their free ends for engaging opposite sides of a knob spindle.

12. A door knob having a tubular extension formed with a non-circular spindle-receiving opening, a member arranged transversely in the knob and having a non-circular opening disposed in alinement with the opening of the knob, and a pair of oppositely-disposed yielding tongues or dogs carried by the member and having their inner 60 free ends normally-disposed in the opening, said free ends of the tongues being provided with angular recesses.

In testimony that I claim the foregoing as my own, I have hereto affixed my signature 65 in the presence of two witnesses.

FRANK E. BEARDSLEY.
